UNITED STATES PATENT OFFICE.

GORDON E. ROEDDING, OF GRAND RAPIDS, MICHIGAN.

DESIGN FOR A WALL POCKET OR SIMILAR ARTICLE.

Application filed October 21, 1925. Serial No. 15,203. Term of patent 3½ years.

To all whom it may concern:

Be it known that I, GORDON E. ROEDDING, a citizen of the Dominion of Canada, residing at No. 929 Grandville Ave. S. W., in the city of Grand Rapids, county of Kent, and State of Michigan, have invented a new, original, and ornamental Design for Wall Pocket or Similar Article, of which the following is a specification, reference being had to the accompanying drawings, forming a part thereof, in which—

I claim:

The ornamental design for a wall pocket or similar article substantially as shown.

GORDON E. ROEDDING.
